STAMP RACK

Filed Oct. 20, 1930

Richard Evans
INVENTOR:

BY *Victor J. Evans*

ATTORNEY.

WITNESS:

UNITED STATES PATENT OFFICE

RICHARD EVANS, OF HIGHLAND PARK, ILLINOIS

STAMP RACK

Application filed October 20, 1930. Serial No. 490,063.

This invention relates to certain novel improvements in stamp racks, and has for its principal object the provision of an improved construction of this character which will be highly efficient in use and economical in manufacture.

The stamp racks now commonly in use support the stamps by receiving the handle which places the stamps in an undesirable position as it makes it difficult to properly view the identification label in this position, causing difficulty in selecting the desired stamp from a number of stamps which may be supported on the rack. It is, therefore, the salient object of this invention to provide a stamp rack which will support the stamps in such position that the identification label on the stamps may be easily read.

Another object of this invention is the provision of an improved stamp rack for supporting rubber stamps in a minimum of space and in such a manner that the identity of the stamp may be readily determined, that is, the stamps may be so constructed that identification labels may be provided on the handle receiving faces of the stamps so that the labels may be readily read and so that time may be saved in selecting the proper stamp from among a number of stamps when it is desired to use a particular stamp.

Another object of the invention is the provision of an improved stamp which may be supported on any horizontal base or suspended from any vertical support.

An additional object of the invention is the provision of an improved stamp rack which is very simple in construction and very economical in manufacture.

Because rubber stamps are generally used hurriedly, the operators frequently stamp them so that the impression is up-side down, which is most unsatisfactory as the mis-stamped impression cannot be easily eradicated to permit proper restamping. Therefore, another object of my invention is to provide a rack which overcomes this objection because stamps can only be placed upon the rack in one and the same position and consequently will be taken from the rack in proper position for use.

Another object is to provide a rack which can be placed, either on a supporting surface such as a desk or table, or be hung from any other means of support.

Another object of my invention is to provide, in combination, rubber stamps and supporting rack, said stamps being provided with recesses which will fit corresponding projections on the rack.

Other objects will appear hereinafter.

The invention consists in the novel combination and arrangement of parts to be herein-after described and claimed.

The invention will be best understood by reference to the accompanying drawing, showing the preferred form of construction and in which:

Fig. 1 is a perspective view depicting a preferred form of construction for my improved stamp rack showing a stamp mounted thereon;

Fig. 2 is a perspective view depicting a typical stamp adapted for use on either the stamp rack depicted in Fig. 1 or on the modified form of construction depicted in Fig. 4;

Fig. 3 is a perspective view of the stamp rack illustrated in Fig. 1 as seen from the rear;

Fig. 4 is a perspective view of a modified form of construction of my improved stamp rack; and

Fig. 5 is a sectional detail view taken substantially on the line 5—5 in Fig. 4, depicting the manner of mounting the stamp on the rack shown in Fig. 4.

While there are numerous stamp racks on the market, these are built so that the rubber stamps are supported by receiving the handle of same which causes the stamp to be suspended by the handle, bringing the identification label, which is then uppermost, on a level plane making it necessary for those desiring to speedily select a certain stamp from a number of stamps so suspended to look down at them from above in order to read the label which is very undesirable and inconvenient in most instances due to surrounding conditions; for example, stamp racks are almost always, for convenience, positioned above desks or tables, or fastened to

a wall above these, within easy reach, but causing the identification label to be above or out of the line of vision. In order to select the desired stamp under these conditions, 5 stamps are generally removed from and replaced onto the rack until the desired one is found which is very unsatisfactory and causes a loss of time. Furthermore the racks now commonly employed are more expensive 10 to manufacture and are so constructed that considerable space is lost when supporting their maximum number of stamps.

It is, therefore, among the several objects of this invention to provide a stamp rack 15 which accommodates a maximum number of stamps in a minimum of space because the stamps can be assembled in close formation on the rack, while it is salient among the objects of this invention to provide a rack which 20 permits the immediate selection of a certain stamp from the number of stamps assembled thereon without necessitating the removal of a number of stamps to identify the one it is desired to use, because the stamps are supported on the rack in such position that the identification label is on a vertical plane and 25 faces the operator. It is likewise an object of this invention to provide a stamp rack which is extremely simple in construction and economical in manufacture, while being efficient in use.

In this invention, there is provided at 10 a main supporting frame in the form of a sheet of any suitable material which is preferably 30 thin sheet metal which may be stamped out 35 in any suitable size and shape. The sheet 10, in the present instance, is attached to suitable upright supports 11 and 12 by means of suitable securing elements 13, and the supports 11 and 12, as shown in Figs. 1 and 3, 40 are substantially triangular in longitudinal extent so that the sheet 10 is inclined at an angle to the vertical. Attached to the support or leg 11 by means of a suitable securing element, such as screw 14, is a foldable, swinging foot 15, and a similar foot 16 is attached 45 to the leg 12 by means of a screw 17 or the like. These feet 15 and 16 are foldable toward each other into the dotted line position of Fig. 3, so that my improved stamp rack generically 50 indicated at 18 may be suspended on any suitable vertical support by means of nails or the like mounted in a vertical wall and extended through the openings 19 in the sheet 55 10 or my improved stamp rack 18 may be supported on the feet 15 and 16 when these feet are extended into the full line position of Figs. 1 and 3, thereby holding the rack 18 in tilted position to permit easy reading of the 60 labels on the stamps.

Integral with the sheet 10 at the bottom thereof is a shelf or flange 21. The outer end of the flange 21 is bent upwardly and folded back upon itself to provide an upstanding 65 element or ridge 22, the purpose of which

will be made apparent presently. Continuous with the outer side and at the lower end of the ridge 22 is a projecting lip 23.

In the use of my improved stamp rack 18, the stamps to be supported thereon, such as the stamp generically indicated at 24, are provided with a slot 25 in one end of the body 26 of the stamp so that the stamps such as 24 may be mounted on my improved rack 18 by arranging the stamps as shown in Fig. 1, 70 75 wherein it will be seen that the ridge 22 projects into the slot 25. This manner of mounting the stamps 24 arranges the stamps so that the long sides 27 are parallel to each other which permits a maximum number of the 80 stamps to be mounted on the ridge 22 in a minimum of space. It is particularly to be noted, further, that this arrangement enables an identifying label disposed on the front side 28 of the stamp to be readily seen so that when 85 it is desired to use a particular stamp the same may be located in a minimum amount of time and without the necessity of handling a number of stamps before finding the desired one as is necessary with the stamp racks used 90 heretofore in the art.

In Fig. 4 there is depicted a modified form of construction and in this instance there is provided a back or supporting frame 29 of stamped sheet metal in which are provided 95 holes such as 30 and 31 so that my improved rack illustrated in Fig. 4, and generically indicated at 32, may be hung upon nails or the like from a vertical support such as the wall 100 of a room.

Integral with the back 29 is a flange or shelf 33 which terminates in an upstanding lip 34. A plurality of spaced apart holes 35 are provided in the flange 33 and removably inserted through these holes are screws 36 105 110 of which are threadedly mounted upstanding elements in the form of small cylinders 37 preferably made of metal and hereinafter to be called "pegs", which can also be cone shaped or otherwise.

There is provided in one end of the body portion 26 of the stamps 24 that are adapted for use with my improved stamp rack 32 a substantially cylindrical bore 38 into which one of the pegs 37 is adapted to fit when the stamp 24 is mounted in position on the rack 32, which bore can also be funnel shaped or otherwise. When the stamps 24 are mounted on the pegs 37 it is apparent that the lip 34 prevents the stamps from being pivoted on the pegs 37 and becoming shifted out of aligned position on the flange 33 and thereby the stamps 24 are kept in aligned position so as to occupy a minimum of space on the flange or shelf 33. When thus mounted in the pegs 37 and shelf 33 it is apparent that the face 28 of the stamps is disposed in a position which permits an identifying label 115 120 125 thereon to be easily and quickly read so that 130

when it is desired to use a particular stamp the same may be quickly located and withdrawn off its peg 37.

While it is manifest that it is not necessary to provide both the bore 38 and the slot 25 in the same stamp it is apparent that this may be done to accommodate the stamp for use on either the rack 18 or the rack 32.

It may be seen, therefore, by referring to Figs. 1 and 4, that the labels on the back 28 of the stamps 24 being arranged in the order of the indicia formed by the characters on the printing face 39 of the stamps the chance of hurriedly grasping a stamp and stamping the impression up-side down is minimized since a very vertical movement is employed in lifting a stamp 24 off from the ridge 22 or one of the pegs 37, this movement consisting of lifting the stamp by means of the handle 40, giving it a quarter turn to the right and then pressing it down to stamp the impression which is a quicker movement than that necessary with the racks heretofore used in the art while this movement also minimizes the risk of mis-stamping the impression which frequently occurs when stamps are suspended by the handle.

From the foregoing description of my invention it is apparent that I have provided improved stamp rack constructions which permits ready reading of the identification labels on the stamps and thereby facilitate the identification of a stamp when it is desired to use the same while it is likewise apparent that rubber stamps or the like may be supported on my improved racks with a maximum economy in space. It is further apparent that my improved racks while accomplishing the several other objects pointed out hereinbefore are extremely simple in construction and, therefore, economical in manufacture.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A stamp rack comprising a supporting frame, a shelf extending substantially horizontally from said frame, and an upstanding member on said shelf, said shelf being adapted to support a stamp having a recess in the body portion thereof to receive said upstanding member, said stamp when so supported having one of its faces resting on said substantially horizontal shelf.

2. A stamp rack comprising a main body

member, a shelf projecting from said body member at the bottom thereof, an upstanding ridge on said shelf, and supporting means for said rack, said means including upright members connected to said body member, and movable feet connected to said upright members at the bottom thereof whereby said feet may be extended to support said body member at an angle with the vertical, said body member having holes therein adapted to permit said rack to be suspended from supporting elements receivable in said holes when said feet are folded toward each other parallel to the extent of said shelf.

In testimony whereof I affix my signature. RICHARD EVANS.
